(57) **CLAIM**

The ornamental design for a tent, as shown and described.

DESCRIPTION

FIG. 1 is a top perspective view of a tent, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view thereof of another state;

FIG. 10 is a bottom perspective view thereof of another state; and,

FIG. 11 is an enlarged detail view of area 11 in FIG. 1. The short evenly spaced broken lines in the drawing illustrate portions of the tent, which form no part of the claimed design. Additionally, the long-dash-short-dash broken lines encircling the enlarged view are shown for the purpose of illustrating the bounds of the enlargement and form no part of the claimed design.
